United States Patent Office.

LIVERUS HULL, OF CHARLESTOWN, MASSACHUSETTS.

Letters Patent No. 81,507, dated August 25, 1868.

IMPROVEMENT IN THE MANUFACTURE OF WHIPS FROM INDIA RUBBER.

The Schedule referred to in these Letters Patent and making part of the same.

TO ALL PERSONS TO WHOM THESE PRESENTS MAY COME:

Be it known that I, LIVERUS HULL, of Charlestown, of the county of Middlesex, of the State of Massachusetts, have invented a new and useful Improvement in Whips; and do hereby declare the same to be fully described in the following specification and represented in the accompanying drawings, of which—

Figure 1 is an external view,

Figure 2 a longitudinal section, and

Figure 3 a transverse section of a whip made in accordance with my invention.

Figure 4 is a side view, and

Figure 5 is an end view of the stock, as prepared for being vulcanized.

In making said whip, I employ cloth covered with a vulcanizable composition, such as is known to and used by manufacturers of India-rubber goods. Such a composition usually consists of caoutchouc or gutta percha and sulphur, or other matter, it being subjected a sufficient period of time to a temperature of about 300° Fahrenheit, changed so as not to be tackey or adhesive to an article when touched by it.

This cloth, with its vulcanizable composition in an adhesive or tackey state, I wind in a roll, and with a taper from one end to the other, until I bring it to the necessary size for the stock or body of the whip. Next, and preparatory to vulcanizing the composition of rubber or gutta percha on such cloth, I cover the roll with a retainer or covering of thread, which may be either wound or braided on the roll, the same being shown in figs. 4 and 5, in which *a* denotes the roll of cloth, and *b* the retainer or thread covering braided on the roll.

This retainer is necessary to hold the cloth in place during the heating-process of vulcanizing it. Furthermore, the retainer compacts the roll, and adds to its strength, particularly when the said retainer is a braided one.

After having thus prepared the stock, and vulcanized it, it is to be covered with one or more finishing-coverings *c* or with the same and one or more "Turks' heads," bands, or tubular or other devices, as fancy may dictate, the snapper or lash being subsequently added.

This mode of making a whip renders it very flexible and suitable for carters, mule-drivers, and others.

The external finishing-covering may be of thread or leather, braided on the stock, or it may be of leather laid around and sewed on the stock.

I claim the whip-stock or body as composed not only of cloth, covered with a vulcanizable composition, and rolled up as set forth, but of a retainer or retaining-covering of thread, either braided or wound thereon for the purpose of supporting the roll during the process of vulcanizing it by heat.

I also claim a whip as composed of the stock or body so made, and one or more coverings of thread, or leather, or other suitable material or materials, either wound, braided, or otherwise properly fixed on such body.

LIVERUS HULL.
